ALIGNMENT MEANS FOR PERFORATING
MULTI-PIPE STRING WELLS

Daniel A. North, Snyder, Tex., assignor, by mesne assignments, to Jersey Production Research Company, Tulsa, Okla., a corporation of Delaware

Filed Aug. 22, 1958, Ser. No. 756,666
12 Claims. (Cl. 166—55.1)

The present invention is directed to apparatus for use in a well containing a plurality of pipe strings. More particularly, the invention is concerned with apparatus for use in a well for perforating only one of a plurality of pipe strings in said well. In its more specific aspects, the invention is concerned with apparatus involving a combination of a plurality of pipe strings and a perforating means for at least one of said pipe strings without perforating the other of the pipe strings.

The present invention may be briefly described as involving apparatus for use in a well comprising in combination a plurality of pipe strings in the well, including at least a first pipe string and at least a second pipe string. The pipe strings are arranged in the well eccentrically and parallel with respect to each other. At least one of said pipe strings has at least a portion of its inner wall of an internal cross-sectional configuration different from the internal cross-sectional configuration of the other pipe string. The internal configuration of the one pipe string is such that it has a major and a minor cross-sectional axis, the one pipe string being oriented with respect to the other pipe string with a selected one of the cross-sectional axes in a direction to avoid, when extended, intersecting the periphery of any of the other pipe strings. An elongated body member is retrievably lowerable and movable through the one pipe string and is provided with perforating means and with biasing means for positioning the body member for movement through the pipe string, the perforating means and the biasing means being vertically spaced from each other such that the perforating means is positioned to perforate the wall of a pipe string in alignment with the selected one of the cross-sectional axes whereby only said one pipe string is perforated. The pipe string which is perforated may thus be perforated in alignment with either the major or minor cross-sectional axis depending on how the pipe string is arranged relative to the other pipe strings.

The internal cross-sectional configuration of the selected one of the pipe strings may be that of an ellipse, while the internal configuration of the other pipe strings may be circular. While the selected one pipe string may have an internal configuration throughout its length different from the internal configuration of the other pipe strings, it may be preferred that the internal configuration of the selected one pipe string while the other portions of the wall of the selected one of the pipe strings may have an internal configuration identical to the internal configuration of the other pipe string. It is understood, of course, that each pipe string may have an internal configuration different from the other pipe strings in the well such that each and every one of the several pipe strings may be separately perforated in a selected zone without perforating the other pipe strings in the well.

Suitable internal configurations having major and minor cross-sectional axes are those such as an elliptical shape or oval or a grooved or slotted shape such that they are major and minor axes. Other suitable configurations may be rectangular and the like.

The elongated body member is provided with a biasing means which suitably may be a spring biased positioning arm or may be drag springs or may include one or more spring loaded bars or leaf type springs and the like.

2

The perforating means may suitably be shaped charges or bullet guns, although it is intended that the perforating means may include mechanical perforating means or chemical perforating means. The perforating means are arranged on the elongated body member vertically spaced from the positioning means and in vertical alignment therewith.

The elongated body member is of a suitable diameter such as to be lowerable through the usual well tubing.

The present invention is quite advantageous and useful in wells containing a plurality of parallel eccentrically placed pipe strings arranged in a bore-hole and cemented in place. One of the pipe strings may communicate with one or more of hydrocarbon productive zones, horizons, sands, intervals, formations, strata, and the like, from which valuable fluid such as hydrocarbons, including oil and/or gas, may be produced. The several parallel eccentrically placed pipe strings may be provided with fluid communication for workover and recompletion operations, and may be positioned for multiple completions.

The present invention will be further illustrated by reference to the drawing in which:

FIG. 1 is a view, partly in section of the device of the present invention.

FIG. 2 is a sectional view taken along the line 2—2 of FIG. 1.

FIG. 3 is a view similar to FIG. 2, providing a slight modification.

FIG. 4 is a view of the perforating gun of FIG. 1 illustrating the positioning means contained therein.

FIG. 5 is a sectional view illustrating a modification of the device as shown in FIG. 1.

FIG. 6 illustrates still another modification of the present invention.

FIG. 7 is a view of a perforating gun containing positioning means adopted for use in the device of FIG. 8.

FIG. 8 is a sectional view illustrating a modification of FIGS. 2 and 3.

Referring now to the drawing and particularly to FIGS. 1 and 2, numeral 11 designates a well bore drilled from the earth's surface, not shown, to penetrate a plurality of subsurface earth strata or formations 12, 13, 14, 15, and 16, in which zones or intervals 12, 14, and 16 may be productive of hydrocarbons.

Arranged in the well bore 11 are pipe strings 17 and 18, which are cemented in the well bore with cement 19. Pipe string 17 may be a conventional pipe string and have a circular cross-sectional configuration while pipe string 18 may have a plurality of sections 20 and 21, which have an internal configuration different from the internal configuration of pipe string 17. For example, the sections 20 and 21 may be elliptical in cross-sectional configuration. Lowerable through the pipe string 18 and movable through the sections 20 and 21 on a conductor cable or wire line 23 is an elongated body member 24 provided with a positioning means 25 having a plurality of perforating means 26 arranged in perpendicular alignment with the perforating means 26 and vertically spaced apart therefrom. The perforating means 26 may be either bullet guns, shaped charges, mechanical type perforators, or chemical perforators as has been described. When the perforating means is properly oriented, it is then operated to perforate the pipe string such as 18.

In FIG. 1 the body member 24 is shown in section 20 for perforating section 20. It is contemplated that the body member 24 may be positioned in section 20 only a sufficient distance to orient the perforating means properly and then the perforating means may be operated to perforate the pipe string 18 in vertical alignment with the major axis of section 20 but above or below section 20, and the like.

As shown in FIGS. 2 and 3, the pipe sections 20 and 21, positioning arms 25, and perforating charges 26 are relatively positioned so that when the section of pipe is perforated the path of the perforating element projected is entirely clear of the pipe 17. This line of travel, as shown, may be aligned with the major or the minor axis of the cross-sectional area of the pipe sections 20 or 21.

It is to be noted that the cross-sectional area across the minor axis of the sections 20 and 21 are at least as large as the cross-sectional area of the pipe 18. For this reason the gun housing 24 can be easily lowered into the sections 20 and 21 whereby the positioning means 25 can then take over and align the gun housing 24 in the proper position.

Referring again to FIG. 1, the pipe 17 is shown extending below the lower end of the pipe 18 and adjacent the formation 16. This formation, as will be understood, can be perforated by a conventional gun such as 29 as there is no danger of perforating any other pipe.

Referring now to FIG. 4, the gun housing 24 is shown attached to the conductor cable 23 and provided with perforating means 26. The body 24 is provided with a window section 27 which has pivotally arranged therein positioning means such as arms 25 which are spring biased outwardly by leaf springs 28.

When a weighted body such as 24 is lowered into a pipe, the torque exerted by the wire line by which it is being lowered causes the body to spin almost continuously. The springs 28 which bias the arms 25 outwardly against the pipe wall do not exert sufficient pressure against the arms to prevent this rotation during the gun's travel through the round pipe 18. It is only when the gun enters the oval shaped sections such as 20 and the arms are extended to their limit along the major axis of the cross-sectional area of the section 20 that this rotation is prevented. It is only when the arms 25 are fully extended that they exert sufficient resistance to stop the body 24 from rotating.

As illustrated in FIG. 5, oval shaped pipe sections such as 20a may be positioned just below the productive intervals such as 12 and 14 and need be only of sufficient length to accommodate aligning action of the arms 25. As can be seen, the positioning arms 25 are located on the lower end of the housing 24a. The sections 20a, of course, could be located just above the formations 12 and 14 whereby the positioning arms 25 would be arranged in the upper end of the gun housing 24a.

Referring to FIG. 6, there is illustrated one oval section 20 which will facilitate the perforation of both the zones 12 and 14. As shown, the arms 25 are located at the upper end of the gun housing 24b to afford perforation of zone 14. If zone 12 is to be perforated, the arms 25 would be located in the lower end of the housing. It will be understood, however, that one pipe section such as 20 or 20a could be placed above or below all of the zones to be perforated; and by means of extensions to the gun housing to correctly place the charges 26, any one of the zones could be selectively perforated.

Referring now to FIG. 7, an elongated body member such as 31, which may be similar to the elongated body member 24, is provided with a recess 32 having a bar 33 biased outwardly from recess 32 by a spring means such as helical coil springs 34. In vertical alignment and vertically spaced from the bar 33 in the recess 32 are a plurality of perforating means 35, which suitably may be bullet guns or shaped charges but in this particular instance may be, for illustration purposes only, considered to be bullet guns.

Referring now to FIG. 8, a well bore 11 has a first pipe string 17 arranged therein which is the same as pipe string 17 of FIGS. 1 and 2 and has a second pipe string 36 provided with an internal slot or groove 37. Arranged in the pipe string 36 is a body member such as 31 having

a perforating means such as 35 which, in this instance, may be a shaped charge. The perforator 31 is provided with a spring biased positioning means such as 33 as described in FIG. 7.

The present invention may incorporate, if desired, a switch circuit to fire the charges which can only be operated when the positioning arms such as 25 and 33 are fully extended.

In employing the present invention for perforating only one of a plurality of pipe strings, the different configuration of the selected one of the pipe strings may be considered as a cam surface which may be either at the bottom of the pipe string, continuous throughout the several hydrocarbon productive intervals or in relatively short sections at intervals throughout the pipe string. These cam surfaces are oriented with respect to the other of the pipe strings and an actuating or positioning means controlled by the cam surface is provided on the perforating gun to orient properly the perforating means such as shaped or jet charges such that only the selected one of the pipe strings is perforated.

The gun perforator or the perforating device comprising the elongated body member and perforating means is lowered through the selected pipe strings such that the perforating means is oriented in the proper direction prior to operating the perforating means to perforate the selected pipe string.

The pipes such as 17 and 18 would be initially connected to each other such as by strapping prior to running in the borehole so as to properly position the section 20 relative to the other pipes.

The sections such as 20 and 21 will usually have a maximum length of about 30 feet but may be shorter or longer as may be dictated by requirements.

As shown in the description taken with the drawing, the several pipe strings are cemented in place in proper orientation such that only one pipe string will be perforated at a time as desired and such that the other pipe string or strings may also be perforated separately without perforating other pipe strings in the well. Thus production may be simultaneously had from a plurality of zones with one pipe string perforated in each zone.

As shown in the drawing, the pipe strings 17 and 18 may be fluidly communicated by a passageway 43 formed by connection 44 which will allow fluid to be circulated from one of the pipe strings to the other of the pipe strings for completion and working-over operations. When this is done, it will be desirable to lower through and seal in one of the pipe strings a tubular member such that fluid may flow upwardly through one of the pipe strings only through the tubular member for circulation and squeezing of cement and other treating reagents as may be desired. A description of such completion and work-over operations may be found in pending application, Serial No. 602,246, now Patent No. 2,938,584, filed August 6, 1956, for John W. Kennedy and Gilbert H. Tausch. While the invention has been described with respect to two pipe strings in a well bore, it may be used with three, four, or more parallel and eccentric pipe strings and is applicable thereto with each pipe string provided with internal configurations different from each other for practice of the present invention for separate perforation of each string in different zones without damaging or perforating any of the other strings.

As shown clearly in FIGS. 1, 4, 5, 6, and 7 of the drawings, the positioning or biasing means may be arranged on either the upper or lower end of the elongated body member or the perforating means may be arranged on the body member above and below the biasing means.

As stated, the present invention is quite advantageous and useful in that simple means are provided for perforating only one pipe string of a plurality of pipe strings in a well.

The nature and objects of the present invention having been completely described and illustrated, what I wish to claim as new and useful and secure by Letters Patent is:

1. For use in a well, apparatus which comprises, in combination, a plurality of pipe strings in said well including at least a first pipe string and at least a second pipe string in said well arranged eccentric and essentially parallel to the first pipe string, one of said pipe strings having at least a portion of its inner wall of an internal cross-sectional configuration different from the internal cross-sectional configuration of the other of said pipe strings, the internal configuration of said one pipe string having a major and a minor cross-sectional axis, said one pipe string being oriented with respect to the other pipe string with a selected one of its cross-sectional axes in a direction to avoid, when extended, intersecting the periphery of any of said other pipe strings, an elongated body member retrievably lowerable and movable through said one pipe string, perforating means carried by said body member, and means carried by and biased outwardly from said body member for positioning said body member for movement through and contact with the wall of said one pipe string, said perforating means being carried by said body member such that said perforating means is positioned on said body member to perforate the wall of the pipe string in alignment with the selected cross-sectional axis which avoids, when extended, intersecting the periphery of said other pipe strings whereby only said one pipe string is perforated.

2. Apparatus in accordance with claim 1 in which the internal configuration of said one pipe string is elliptical and the internal configuration of said other pipe string is circular.

3. Apparatus in accordance with claim 1 in which the inner wall of said one pipe string is provided with a grooved internal configuration and the inner wall of the other pipe string is provided with a circular internal configuration, said one pipe string being oriented with respect to the other pipe string such that the selected one of the cross sectional axes is the major axis.

4. Apparatus in accordance with claim 1 in which the selected axis is the major axis.

5. Apparatus in accordance with claim 1 in which the selected axis is the minor axis.

6. For use in a well, apparatus which comprises, in combination, a plurality of pipe strings in said well including at least a first pipe string and at least a second pipe string in said well arranged eccentric and essentially parallel to the first pipe string, at least one elongated section in one of said pipe strings having an internal cross-sectional configuration different from the internal cross-sectional configuration of the other of said pipe strings, the internal configuration of said section in said one pipe string having a major and a minor cross-sectional axis, said section being oriented with respect to the other pipe string with its major cross-sectional axis in a direction to avoid, when extended, intersecting the periphery of any of said other pipe strings, an elongated body member retrievably lowerable through said one pipe string and movable in said section, shaped charge perforating means carried by said body member, and means carried by and biased outwardly from said body member vertically spaced from said perforating means for positioning said body member for movement through and contact with the wall of said section in said one pipe string, said perforating means and said positioning means being carried by said body member such that said per-

forating means is positioned to perforate the wall of said one pipe string in vertical alignment with the major cross sectional axis of said section whereby only said one pipe string is perforated.

7. Apparatus in accordance with claim 6 in which the biasing means is carried on the upper end of said body member.

8. Apparatus in accordance with claim 6 in which the biasing means is carried on the lower end of said body member.

9. Apparatus in accordance with claim 6 in which the perforating means are arranged on said body member above and below said biasing means.

10. For use in a well, apparatus which comprises, in combination, a plurality of pipe strings in said well including at least a first pipe string and at least a second pipe string in said well arranged eccentric and essentially parallel to the first pipe string, at least one elongated section in one of said pipe strings having an internal cross-sectional elliptical configuration, the internal cross-sectional configuration of the other of said pipe strings being circular, said section being oriented with respect to the other pipe string with the major cross-sectional axis of the elliptical configuration in a direction to avoid, when extended, intersecting the periphery of any of said other pipe strings, an elongated body member retrievably lowerable through said one pipe string and movable in said section, shaped charge perforating means carried by said body member, and means carried by and biased outwardly from said body member vertically spaced from said perforating means for positioning said body member for movement through and contact with the wall of said section in said one pipe string, said perforating means being carried by said body member such that said perforating means is positioned to perforate the wall of one pipe string in vertical alignment with the major cross-sectional axis of said section whereby only said one pipe string is perforated.

11. An apparatus for completing a well at a plurality of production levels comprising a plurality of conduits of different lengths, each of said conduits extending with its lower end to a level within a separate production interval, and at least one of said conduits being provided at a level adjacent the productive interval to which it extends with an alignment section having a noncircular cross-section with a major and a minor axis, said one of said conduits being oriented with respect to the other conduits to position a selected one of said axes of said section in a direction to avoid, when extended, intersecting the periphery of any of said other conduits.

12. An apparatus as defined in claim 11 in combination with an alignment tool arranged within said alignment section and spaced from the inner wall thereof by outwardly biased positioning means in said tool, said positioning means being movable in a radial direction and so disposed in said tool as to lie on said major axis of said alignment section.
